CARPET.

No. 15,511.

Patented Nov. 4, 1884.

UNITED STATES PATENT OFFICE.

ARTHUR L. HALLIDAY, OF NEW YORK, N. Y., ASSIGNOR TO THE BIGELOW CARPET COMPANY, OF CLINTON, MASSACHUSETTS.

DESIGN FOR A CARPET.

SPECIFICATION forming part of Design No. 15,511, dated November 4, 1884.

Application filed August 9, 1884. Term of patent 3½ years.

To all whom it may concern:

Be it known that I, ARTHUR L. HALLIDAY, of New York, county and State of New York, have invented and produced by my own industry, genius, efforts, and expense a new and original Design for a Carpet, of which the following is a correct description, reference being had to the annexed photograph, which represents a face view of my new carpet.

This invention relates to a new ornamentation of a carpet, oil-cloth, or similar fabric; and it consists of the novel grouping and outlines of figures hereinafter described.

In the photograph, the letters a b c represent groups of flowers surrounded by foliage ¹⁵ d, which is interspersed with flowers, the upper part of the band A, containing these figures, being lined with floral group e. Above the said band is stripe B, having geometrical figures f and conventional leaves g, as shown. ²⁰

I claim—

The design for a carpet or other fabric, the same consisting of the figures A a b c d e B f g, substantially as shown.

ARTHUR L. HALLIDAY.
